UNITED STATES PATENT OFFICE.

CARL E. CHRISTOPHEL, OF PEARL RIVER, NEW YORK, ASSIGNOR TO DEXTER FOLDER COMPANY, OF PEARL RIVER, NEW YORK, A CORPORATION OF NEW YORK.

FEEDING-MACHINE.

1,258,744.

Specification of Letters Patent. Patented Mar. 12, 1918.

Application filed October 31, 1916. Serial No. 128,805.

To all whom it may concern:

Be it known that I, CARL E. CHRISTOPHEL, a subject of the German Emperor, residing at Pearl River, county of Rockland, and 5 State of New York, have invented certain new and useful Improvements in Feeding-Machines, of which the following is a specification.

This invention relates to sheet-feeding machines and more especially to that class of feeding machines which are peculiarly serviceable for feeding sheets of cardboard or the like. The primary object of this invention is to provide an improved device 10 for separating sheets of cardboard from a pile as they are being fed one by one from the pile. One of the objects of the present invention is to provide an improved construction in which the several coöperating 15 parts are more closely related to each other. Another object is to provide an improved sheet-separating mechanism that will be 20 simple, durable and efficient.

Other and further objects will appear in 25 the specification and be pointed out in the appended claims, reference being had to the accompanying drawings which exemplify my invention in its preferred embodiment. In the drawings,

30 Figure 1 is a side elevation of sheet-separating mechanism, constructed in accordance with the principles of the present invention; parts being broken away and parts shown in section;

35 Fig. 2 is a similar side elevation showing the parts in changed positions.

Fig. 3 is a similar side elevation showing a further stage of the operation;

40 Fig. 4 is a rear elevation of the mechanism corresponding to Fig. 1, the fixed support being shown in section;

Fig. 5 is a top plan view of the same;

45 Fig. 6 is a top plan view of the suction cylinder, on an enlarged scale, parts being shown in section; and

Fig. 7 is a fragmentary rear elevation of the foot or lower end of the sliding frame, parts being broken away and parts shown in section.

50 Referring more particularly to the draw-

ings, the embodiment of my invention shown therein, includes a fixed bracket or support 1 to which a guide is adjustably connected by means of a stud or bolt 2. Said guide comprises a block 3 provided 55 with a rearwardly projecting lug 4 which pivots on stud or bolt 2. Depending from the block 3 are spaced guide rods 5 to which are connected collars 6 which constitute stops for limiting the downward movement 60 of a slide or frame which is reciprocably mounted on the rods 5 and comprises a block 7 which carries a forwardly presented bracket 8 provided with a laterally projecting depending foot 9 and an upwardly forwardly projecting bracket arm 10. As shown best in Figs. 1 and 7, the foot 9 is provided with a pin or extension 11 which is adapted to rest on a pile of sheets when the slide or frame is lowered. For this purpose, the bottom surface of said foot comprises a facet 12 which in lowered position lies flat on the pile and a facet 13 which is angularly disposed thereto and against which a portion of the top sheet is drawn 75 in the manner to be hereinafter pointed out.

It will appear from Figs. 1 and 7 that foot 9 is provided with an annular slot for journaling a circularly formed plate 14 which projects laterally from the shank 15 of a cradle which includes a strap or band 16 for mounting a cylinder 17 provided at its lower end with a sucker 18. A screw 19 secures said strap or band around the cylinder. Secured to the top wall of foot 9, 80 is the curved plate 20 of a bracket arm 21 which engages the lateral face of the shank 15 and prevents the lateral displacement of the cylinder-carrying cradle. A piston 22 (not shown on the drawings) is provided 85 with a piston rod 22 which carries a rigid abutment or collar 23 which limits the movement of a sleeve 24 which is pressed upon from above by a spring 25 which surrounds the rod 22 and is confined between the sleeve 90 24 and an abutment 26 which is adjustably connected to the rod 22. The sleeve 24 is pivotally connected at 27 with one end of a rod or lever 28 which has its upper end 95 pivotally connected at 29 with the swinging 100

end of a link 30 which is pivoted at 31 upon the bracket 10. A fixed stop or pin 32 limits the downward movement of guide link 30. Said rod or lever 28 is provided with a slot 33 within which slides a pin 34 carried by a crank arm 35 which is keyed to a cam shaft 36. Referring now to Figs. 4 and 5, the cam shaft 36 has keyed thereto a bevel gear 37 which meshes with a bevel gear 38 keyed to a shaft 39 which receives its power through universal connections which maintain the power-transmission without interfering with the reciprocating movements of the slide or frame 8. Keyed to the cam shaft 36 is a cam 40 over which runs a cam roller 41 journaled in the outer end of a cam lever 42 which oscillates about a stud 43 but has a portion thereof inclined forwardly and downwardly to adapt it to hook under and to support the edge or corner of a sheet which has been lifted by an upward movement of the sucker 18. Projecting rearwardly from the slide or frame 8 is an arm or bracket 45 which supports a blow pipe or nozzle 46 which may receive compressed air from any suitable source. In order to impart a lifting movement to the clamping foot whenever such a movement is permitted by the cam 40, a spring 47 is connected at one end to a pin 48 carried by the cam lever 42, the other end of said spring being connected to a pin 49 which projects laterally from a forwardly extending arm or bracket 50. The operation of my improved mechanism may now be briefly explained as follows:

According to Fig. 1 of the drawings, cam 40 has just permitted the clamping foot 44 to move upwardly, thus permitting the slide or frame 8 to fall on the guide rods 5 until the foot 11 rests upon the pile of sheets. Spring 47 has also acted to elevate clamping foot 44. By means of the angular movement of slotted cam bar 28, the cylinder 17 has been moved into an upright position with the sucker 18 pressed closely to the top sheet of the pile, the piston being depressed in cylinder 17. The cam shaft 36 rotates in an anti-clockwise direction, thus moving the piston upwardly in the cylinder 17 and causing the sucker 18 to grip the top sheet of the pile. As the upward movement of the piston goes on, the cylinder is tilted to the left on the foot 11 as a pivot until it assumes the position shown in Figs. 2 and 3. Cam 40 now begins to act upon cam lever 42, thus forcing the clamping foot 44 down on to the pile and eventually causing said slide or frame 8 to be moved upwardly on the guide rods 5 and lifting the foot 11 from the pile, thus releasing the top sheet as soon as the piston begins to move downwardly to break the action of sucker 18. The tilting movement of cylinder 17 has served to

lift the edge or corner of the sheet above 65 the hooked lower end of clamping foot 44 which sustains it above the pile after the sucker 18 has released it. A blast of air from the pipe or nozzle 46 may then be introduced under the top sheet which is then 70 withdrawn from the pile in a well known manner.

I claim:

1. In a machine of the character described, a sheet-engaging instrumentality reciprocable toward and away from a pile of sheets, a foot clamp movably connected to said sheet-engaging instrumentality, and means for moving said foot clamp down on to said pile, the movement of said foot clamp being 80 adapted to reciprocate said sheet-engaging instrumentality.

2. In a sheet-feeding machine, a reciprocable frame, a sheet-gripping instrumentality movable on said frame, means for moving said frame into and out of engagement with said pile, and means for moving said sheet-gripping instrumentality on said frame to raise a portion of the top sheet, said means for moving the frame including 90 a clamp foot movably mounted on said frame and adapted by its engagement with the pile to lift said frame therefrom.

3. In a machine of the character described, a reciprocable frame, means including a 95 clamping foot for raising and lowering said frame, sheet-gripping means movably mounted on said frame, and means for operating said sheet-gripping means to adapt it to grip a sheet near one extreme of its 100 movement relatively to said frame and to release said sheet near the other extreme of its movement.

4. In a machine of the character described, a reciprocable frame, means including a 105 clamping foot for raising and lowering said frame, sheet-gripping means movably mounted on said frame, and means for operating said sheet-gripping means to adapt it to grip a sheet near one extreme of its 110 movement relatively to said frame and to release said sheet near the other extreme of its movement, said sheet-gripping means being oscillatable about a portion of said reciprocable frame which rests upon the top 115 sheet of a pile when said frame is in lowered position.

5. In a machine of the character described, a reciprocable frame, means including a clamping foot for raising and lowering 120 said frame, sheet-gripping means movably mounted on said frame, and means for operating said sheet-gripping means to adapt it to grip a sheet near one extreme of its movement relatively to said frame and to 125 release said sheet near the other extreme of its movement, said sheet-gripping means including a cylinder pivotally connected to

- said frame, a sucker carried by said cylinder, a piston movable in said cylinder, and means for moving said piston in said cylinder to successively make and break the suction therein. 5
6. In a machine of the character described, a guide, a slide reciprocably mounted on said guide and provided with a foot adapted to rest upon a pile of sheets, a sheet-gripping device oscillatably mounted on said slide, and means for oscillating said sheet-gripping device and operating said device to alternately grip and release a sheet, said sheet-gripping device comprising a suction cylinder pivotally mounted on said slide and a piston reciprocable in said cylinder and connected up with said oscillating means. 10
7. In a machine of the character described, a guide, a slide reciprocably mounted on said guide and provided with a foot adapted to rest upon a pile of sheets, a sheet-gripping device oscillatably mounted on said slide, and means for oscillating said sheet-gripping device and operating said device to alternately grip and release a sheet, said sheet-gripping device comprising a suction cylinder pivotally mounted on said slide and a piston reciprocable in said cylinder and connected up with said oscillating means, said oscillating means being adapted to reciprocate the piston within said cylinder. 15
8. In a device of the character described, a reciprocable slide, a cylinder pivotally mounted on said slide, a piston reciprocable in said cylinder, a rotary shaft journaled in said slide, and means connecting said shaft and said piston for reciprocating said piston and oscillating said cylinder. 20
9. In a device of the character described, a reciprocable slide, a cylinder pivotally mounted on said slide, a piston reciprocable in said cylinder, a rotary shaft journaled in said slide, and means connecting said shaft and said piston for reciprocating said piston and oscillating said cylinder, said connecting means including a link connected to said piston and a crank arm keyed to said shaft and having a pin and slot connection with said link. 25
10. In a machine of the character described, a reciprocable slide, a suction cylinder pivotally mounted on said slide, a piston reciprocable in said cylinder, said piston being provided with a piston rod, a shaft journaled in said slide, a crank arm keyed to said shaft, a slotted link oscillatably connected to said piston rod and slidably connected to said crank arm, and means adapted to be operated by said shaft for periodically raising said slide. 30
11. In a machine of the character described, a reciprocable slide, a suction cylinder pivotally mounted on said slide, a piston reciprocable in said cylinder, said piston being provided with a piston rod, a shaft journaled in said slide, a crank arm keyed to said shaft, a slotted link oscillatably connected to said piston rod and slidably connected to said crank arm, and means adapted to be operated by said shaft for periodically raising said slide. 35
- ton reciprocable in said cylinder, said piston being provided with a piston rod, a shaft journaled in said slide, a crank arm keyed to said shaft, a slotted link oscillatably connected to said piston rod and slidably connected to said crank arm, and means adapted to be operated by said shaft for periodically raising said slide, said periodically operated means including a lever pivotally mounted on said slide and provided with a clamping foot movable into and out of engagement with a pile of sheets. 40
12. In a machine of the character described, a reciprocable slide, a suction cylinder pivotally mounted on said slide, a piston reciprocable in said cylinder, said piston being provided with a piston rod, a shaft journaled in said slide, a crank arm keyed to said shaft, a slotted link oscillatably connected to said piston rod and slidably connected to said crank arm, and means adapted to be operated by said shaft for periodically raising said slide, said periodically operated means including a lever pivotally mounted on said slide and provided with a clamping foot movable into and out of engagement with a pile of sheets, said clamping foot having a hooked lower end adapted to provide a support for the buckled edge of a sheet raised by said suction cylinder. 45
13. In a machine of the character described, a reciprocable slide, a suction cylinder pivotally mounted on said slide, a piston reciprocable in said cylinder, said piston being provided with a piston rod, a shaft journaled in said slide, a crank arm keyed to said shaft, a slotted link oscillatably connected to said piston rod and slidably connected to said crank arm, and means adapted to be operated by said shaft for periodically raising said slide, and a blast pipe nozzle mounted on said slide and suitably arranged to introduce a blanket of air under the edge of a sheet which has been raised by said suction cylinder. 50
14. In a machine of the character described, a reciprocable slide provided with a depending foot adapting said slide to rest on a pile of sheets, a suction cylinder oscillatable on said foot, means for evacuating said suction cylinder to adapt it to grip the top sheet on said pile, and means for simultaneously oscillating said suction cylinder to lift a portion of the top sheet. 55
15. In a machine of the character described, a reciprocable slide provided with a depending foot adapting said slide to rest on a pile of sheets, a suction cylinder oscillatable on said foot, means for evacuating said suction cylinder to adapt it to grip the top sheet on said pile, and means for simultaneously oscillating said suction cylinder to lift a portion of the top sheet, said slide being provided with a clamping foot pe- 60

riodically movable on said slide into and out of engagement with the pile, said clamping foot being adapted by its movement to elevate said slide.

5 16. In a machine of the character described, a guide, a slide reciprocable thereon, and adapted to rest on a pile of sheets, suction-producing means oscillatable on said

slide into position to grip the top sheet of said pile and out of said position to lift 10 a portion of said sheet, and means movable on said slide into position beneath the lifted portion of said top sheet and adapted to lift said slide from the pile.

CARL CHRISTOPHEL.
